UNITED STATES PATENT OFFICE.

CORNELIS ARIAN MULDER, OF AMSTERDAM, NETHERLANDS.

SAFETY-RAZOR.

1,271,352.

Specification of Letters Patent.

Patented July 2, 1918.

Application filed July 16, 1917. Serial No. 180,917.

To all whom it may concern:

Be it known that I, CORNELIS ARIAN MULDER, a subject of the Queen of the Netherlands, residing at Amsterdam, Netherlands, 5 have invented certain new and useful Improvements in Safety-Razors, of which the following is a specification.

This invention relates to a safety-razor, and has for its object to provide a simple 10 and cheap instrument which has all the advantages of the known safety-razors and besides this also the special advantage that the blades used in the instrument can be manufactured at very small cost.

15 The holder of the instrument consists for a part of a combination of known features; the essential part is however the blade which is very narrow, measuring in width about $\frac{5}{32}$ of an inch.

20 In carrying out the invention I employ the novel combination, arrangement and details of construction hereinafter shown, described, and specifically claimed.

In the accompanying drawings illustrative of the invention Figure 1 is a side-view 25 of the razor. Fig. 2 is a plan view of the base-plate which carries the screw stem and pins for the securing of the blade. Fig. 3 is a plan view of the toothed closing-plate 30 provided with holes for the pins of the base-plate, the latter and the closing-plate together forming a jaw for clamping the blade. Fig. 4 is a side-view of the blade on an enlarged scale.

35 The base-plate *a* is provided with pins *e* and *f* projecting in the same direction as the stem *g* on which the holder *d* is screwed. The closing-plate *b* has such a shape, that when placed on the base-plate it covers the latter, while the pins *e* and *f* of the base-plate protrude through the co-incident holes *i* and *j* in the closing plate. The blade *c*, preferably sharpened by grinding it off at 40 one side in the manner of a chisel, is so placed on the base-plate that its rear edge abuts against the pins *f*; and the holder *d* when screwed on the stem *g* exerts a clamping action on the blade, the closing-plate and the base-plate, the blade being clamped between the front-edges of the base-plate and the closing-plate and secured tightly in an oblique direction with regard to the plane 45 of the base-plate.

The closing-plate is provided with teeth

h which are disposed in a sidewise inclined direction, while the row of teeth is adjoined at both ends by the broader teeth *k*. These teeth *k* cover the ends of the blade so that the sharp corner of the blade cannot injure the skin. Besides this the blades are not bound to an exact length so that precision-work is not necessary.

The described construction of the apparatus whereby the very narrow blade is secured at the front-edges of the jaw, and further the combination of very broad corner-teeth with the blade in contact (up to the edge) with the row of teeth disposed in a sidewise inclined direction render it possible to use very cheap blades without causing any detriment to the razor.

When using the known safety-razor, the instrument must be entirely detached in its constituents, in order to remove the blade and clean it. For detaching the blade from the instrument according to the invention, it suffices to give the holder one loosening turn, the blade will then fall out of the instrument and can be cleaned or thrown away as the cost of the blade is very low.

Having described my invention, what I claim and desire to secure by Letters Patent is:

In a safety razor, the combination of a base-plate and a closer-plate, constituting 55 companion elements, the base-plate having a stem for which the closer-plate has an opening, a holder threaded on the stem to hold the closer-plate against the base-plate and to cause said plates to function as a 60 clamping jaw, one of said plates having a pair of pins projecting toward the other plate and the latter having openings for said pins, and a narrow blade adapted to be 65 clamped by said plates between the front edges thereof and with its rear edge to abut 70 said pins, said blade being disposed wholly at one side of said stem and being freely movable from between said plates when the 75 holder is turned to relieve the clamping 80 pressure of said plates.

In testimony whereof I have hereunto set my hand in presence of two subscribing witnesses.

CORNELIS ARIAN MULDER.
